UNITED STATES PATENT OFFICE

154,825

DESIGN FOR A JEWELRY BOX

Lawrence M. Weil, Buffalo, N. Y.

Application March 8, 1948, Serial No. 144,981

Term of patent 7 years

(Cl. D86—9)

To all whom it may concern:

Be it known that I, Lawrence M. Weil, a citizen of the United States, residing at Buffalo, in the county of Erie and State of New York, have invented a new, original, and ornamental Design for a Jewelry Box, of which the following is a specification, reference being had to the accompanying drawing, forming part thereof, and in which:

Fig. 1 is a perspective view of a jewelry box showing my new design, with the cover in opened position;

Fig. 2 is a further perspective view of the jewelry box with the cover in closed position; and

Fig. 3 is a top plan view.

I claim:

The ornamental design for a jewelry box, substantially as shown.

LAWRENCE M. WEIL.
